(57) **CLAIM**

The ornamental design for a mop combo as shown and described.

DESCRIPTION

FIG. 1 is a perspective view of a mop bucket showing the claimed design;

FIG. 2 is another perspective view of the mop bucket thereof;

FIG. 3 is a front elevational view of the mop bucket thereof;

FIG. 4 is a rear elevational view of the mop bucket thereof;

FIG. 5 is a left side view of the mop bucket thereof;

FIG. 6 is a right side view of the mop bucket thereof;

FIG. 7 is a top plan view of the mop bucket thereof;

FIG. 8 is a bottom plan view of the mop bucket thereof;

FIG. 9 is a perspective view of a mop showing the claimed design;

FIG. 10 is another perspective view of the mop thereof;

FIG. 11 is a front elevational view of the mop thereof;

FIG. 12 is a rear elevational view of the mop thereof;

FIG. 13 is a left side view of the mop thereof;

FIG. 14 is a right side view of the mop thereof;

FIG. 15 is a top plan view of the mop thereof;

FIG. 16 is a bottom plan view of the mop thereof;

FIG. 17 is a view of the mop when placed vertically thereof;

FIG. 18 is a partial enlarged view of FIG. 10 thereof; and,

FIG. 19 is a view of the mop in the mop bucket thereof. The broken lines depict portions of the mop combo that form no part of the claimed design.

1 Claim, 19 Drawing Sheets
